OIL CRACKING PROCESS

George C. Peckham, Los Angeles, Calif.

Application April 27, 1935, Serial No. 18,612

4 Claims. (Cl. 196—70)

This invention deals generally with the cracking of petroleum oils, and relates more particularly to systems in which the oil is cracked by direct contact with a suitable molten metal or inorganic salt heated to cracking temperatures. In some of its aspects, the invention may be regarded as an improvement in the general type of cracking process described in a copending application, Ser. No. 637,116, filed by Wayne A. S. Harmon on Process for cracking hydrocarbons.

The present process may be broadly characterized as an oil cracking system in which preheated liquid oil, or oil vapors, or both, are injected into a stream of molten metal being circulated at a fairly rapid and uniform rate of flow by a suitable mechanical means, such as a rotary pump. The molten metal is maintained in a circuitous path of flow passing through a heating zone, wherein the temperature of the metal is raised sufficiently high to supply the heat necessary to crack the hydrocarbon, and thence in a continuous and uniform velocity stream vertically through the cracking zone. The hydrocarbon is cracked at a temperature sufficiently high to reduce the residue to a dry and very finely divided carbon which rises to the surface of the molten metal in the cracked zone and is continuously swept away in the cracking vapor stream into a separating chamber. The present system differs in one important respect from the process described in the Harmon application referred to above in that the hydrocarbon and molten metal flow in the same upward direction within the cracking zone, whereas in the Harmon system the oil and metal streams flow counter-currently with the oil vapors rising through a down-flowing stream of molten metal.

One of my principal objects is to provide a process for cracking oil to a dry powdered carbon residue by direct contact with a stream of molten metal flowing continuously under the influence of a mechanical and positive acting circulating means; also, to provide a process of this type that is particularly adaptable to flexibility and accuracy of control and to the maintenance of closely controlled cracking temperatures. Two of the principal features responsible for the accomplishment of this object are the circulation of the molten metal in a controllably uniform and constant rate of circulation, and the passage of the metal and hydrocarbon in the same upward direction within the cracking zone.

Experiments have shown that in order to obtain the most efficient oil conversion and to insure the continuous formation and removal of

the desired residue, i. e., dry powdered carbon, certain heating and temperature conditions must be maintained in the cracking zone. In the first place, with the charging stock being continuously injected into the cracking zone, the amount of heat required to crack the oil must be proportionate to the rate of feed and must be supplied at a correspondingly constant rate. The maximum temperature to which the vapors are heated must be sufficiently high to reduce the residue to dry carbon, but without substantial overheating that would result in the production of excessive amounts of fixed gas. Since the molten metal stream is the medium by which heat is supplied to the oil undergoing cracking, it will be seen that the amount and rate of heat supplied to the cracking zone, as well as the maintenance of particular temperature conditions therein, are dependent upon the rate of molten metal circulation; hence the necessity for maintaining the metal in a continuously moving stream and for controlling the rate of its flow is of primary importance.

By reason of the adaptability of the present system to absolute and accurate control of the amount and rate of molten metal circulation, I am able to control with corresponding accuracy the heating and temperature conditions in the cracking zone and therefore the character and proportions of the products resulting from the cracking reaction. At the same time, I am able to insure the reduction of the residue to a fine carbon powder and to effectively remove carbon from the cracking zone to the extent that even after long periods of operation, the cracking chamber will remain free from any substantial accumulations of carbon.

Other objects of the invention are directed to the provision of a system capable of producing abnormally large percentage yields of cracking gasoline possessing high anti-knock or octane rating, and a minimum of sulphur and other corrosive bodies. The cracked gasoline product is further characterized by the unusually small amounts of acids or clays required for its treatment to finished gasoline. Various features of the invention contribute to the accomplishment of these general objects, and while all such features might at this point be preliminarily referred to and discussed, it is believed that a better and more ready understanding of the entire invention can be given by proceeding directly with a description of one illustrative form thereof. For purposes of description, reference is had to the accompanying drawings, in which:

Fig. 1 is a general diagrammatic view showing a preferred form of oil cracking system embodying the invention;

Fig. 2 is a fragmentary enlarged section taken on line 2—2 of Fig. 1; and

Fig. 3 is an enlarged fragmentary view, showing the upper portion of the oil cracking chamber.

Referring first to Fig. 1, the retort wall structure, generally denoted by the reference numeral 10, encloses a series of heating chambers which may be individually fired or heated by combustion gas circulation from a primary heating chamber 11 equipped with burners 12. A closed heating chamber 12a containing a molten metal circulating pump 13, hereinafter referred to more in detail, communicates with chamber 11 through opening 14. The main combustion gas stream leaving chamber 11 passes through opening 15 into chamber 16, through which the hot gases flow upwardly along the shell 17 and out through opening 18 into chamber 19 containing carbon trap 20. The gases then pass out through opening 21 into chamber 22 containing a comparatively large volume shell 23 which forms the later described gas conversion chamber.

The vertically positioned shell 17 forms an externally heated cracking chamber, and may conveniently comprise upper and lower cylindrical sections 17a and 17b of comparatively larger and smaller diameters, respectively. Oil is subjected to cracking in shell 17 by direct contact with a continuously circulated stream of molten metal 25, (see Fig. 3) typically and preferably molten lead. The molten metal is discharged through inlet line 26 into the lower portion of section 17b of the cracking chamber, and is then caused to flow upwardly through the cracking zone in a rapidly moving stream. As best illustrated in Fig. 3, the molten metal 25 flows laterally from section 17a of the cracking chamber through shell 27 into line 28 connecting with the section inlet 29 of pump 13.

Pump 13 is of the rotary impeller type, operating to circulate the molten metal in a non-pulsating, uniform velocity stream, and the pump structure is shown diagrammatically as comprising a body 13a containing an impeller 30 driven through shaft 31 by motor 32. In being contained substantially entirely, except for the motor, within chamber 12a, the pump will be externally heated to a temperature sufficiently high to avoid solidification of any of the circulating metal within the pump. Molten metal flowing upwardly within the pump body above the impeller is returned to the suction line 28 by way of drain pipe 33.

The molten metal is discharged by pump 13 through pipe 34 and heating coil 35 into the cracking chamber via inlet line 26. While being circulated through the heating coil 35, the metal stream is heated to a temperature sufficiently high to maintain the hereinafter described cracking conditions within shell 17. By varying the operating speed of pump 13, the rate at which the molten metal is circulated, and the velocity of the metal stream flowing upwardly through the cracking chamber, may be closely adjusted to control the cracking operation by varying the time period during which the oil is maintained in contact with the metal stream. As illustrated in Fig. 2, the molten metal may be drained from the system through a valve line 36 extending through a bottom closure 17c positioned within shell 17b a short distance below the inlet 26.

Preferably, the oil charging stock is preheated and partially vaporized prior to being injected into the cracking zone, and while it is understood that the oil preheating operation may be carried out by any suitable method and apparatus, I have shown a typical preheater 37 of the shell still type into which the charging stock is fed through line 38. The charging stock will be preheated in shell still 37 to a temperature ranging from say 400° to 550° F., under whatever back pressure is imposed by the cracking system. The unvaporized oil flows from still 37 through line 39, and is discharged by pump 40 through line 41 and injection nozzle 42 into a suitable point within chamber 17b above the 15 molten metal inlet 26.

The injection nozzle structure 42 has been specially designed with the view of preventing the charging stock from carbonizing and clogging the injection orifice, by continuously circulating a stream of oil past the orifice and the injection valve, the oil temperature being kept sufficiently low by continuous circulation to prevent carbonizing at the point of injection into the cracking zone. Referring to Fig. 2, the injection valve structure 42 comprises a body 43 welded or otherwise attached at 44 to the side of shell 17b, and having a discharge orifice 45 controlled by a needle valve 46 extending through a suitable stuffing box 47. Pipe 41 connects with a U-shaped passage 48 through an enlarged portion 48a of which the needle valve 46 extends. The outlet side 48b of the passage connects with a return flow line 49 leading back to shell still 37. The oil injection pressure within passage 48a 35 of the injection nozzle is controlled by an adjustable pressure regulating valve 50 in line 48, acting to maintain a predetermined back pressure against pump 40.

In operation, a portion of the circulating oil stream, dependent on the oil pressure and the adjustment of needle valve 46, is discharged through orifice 45 directly into the upwardly flowing stream of molten metal within chamber 17b. The remaining portion of the oil stream flowing through passage 48 is circulated across the valve controlled end of orifice 45 and in contact with the valve itself, and is circulated back through passage 48b and line 49 to the preheating still. Although the oil is preheated, its temperature will be below that at which appreciable cracking or carbonization will occur, and as a result of the continued circulation past the injection port and valve, the temperatures in the vicinity of the orifice will be kept sufficiently low to prevent the orifice and valve from collecting carbon to an extent necessitating frequent shutdowns for cleaning.

Preferably the molten metal will be maintained in the cracking zone at a temperature sufficiently high to vaporize substantially all the volatile constituents of the oil, so that the immediate products of the cracking reaction will consist of cracked vapors and a more or less dry powdery carbon residuum. Under these conditions, the temperature of the molten metal within the cracking zone will range in the neighborhood of from 1000° to 1400° F., depending upon the nature of the charging stock. The injected oil and molten metal flow upwardly together within the cracking zone; the depth of the molten metal column, the rate of oil injection, and the velocity of the molten metal stream all being controllable and regulated to maintain the oil in contact with the molten metal for that period 75

of time which, under the existent conditions, will most efficiently promote the cracking reaction to the desired extent.

- 5 The powdered carbon residue collects on the surface 52 of the metal stream and is continuously removed in the stream of cracked vapors flowing from the cracking chamber. As the molten metal flows from chamber 11a through shell 21 to the outlet line 28, the cracked oil vapors 10 sweep across the surface 52 of the metal, picking up the powdered carbon residue, and carrying it out through lines 53 and 54 into carbon trap 20, wherein the carbon settles out into the base of the trap. The carbon may be intermittently removed from the trap, or continuously as by means 15 of an ejector 55 connecting with the carbon outlet pipe 56. In the event the upward cracked vapor of gas velocity through the surface of the molten metal in chamber 11a is sufficiently high, 20 the vapors and carbon residue may be discharged from the top of the chamber through line 58 connecting with pipe 54, or, if desired, the cracked vapors may be discharged through both lines 53 and 58.
- 25 The preheated oil vapors passing from still 37 through lines 60 and 61 preferably are combined with the cracked oil vapors leaving the cracking chamber, although if for any reason it is found desirable to treat the preheated oil vapors 30 separately from the cracked vapors, the former may be passed through line 62 for condensation or any other further treatment. For the purpose of combining the preheated and cracked oil vapors, the former may be conducted through lines 35 63 and 64 into the top of chamber 11a, or at any other suitable point in the cracked oil vapor stream leaving the molten metal 25, the combined vapors then flowing through lines 58 and 54 to the carbon trap 20. In order to assist the removal of the powdered carbon residue from the 40 surface 52 of the metal stream, a portion or all of the preheated oil vapors may be passed through a line 65 leading at 66 into shell 21, and terminating in an upwardly directed outlet 67 located a 45 short distance below the molten metal surface 52. The vapors being discharged upwardly from the outlet 67, agitate the surface of the metal stream and blow the carbon toward the cracked vapor outlet 53 and into the transversely flowing 50 stream of cracked vapors. It is to be understood that while it is most convenient to utilize a portion or all of the preheated vapors as a gas for agitating and blowing the carbon residue from the surface of the metal stream in the manner explained, any suitable gas derived from a source 55 extraneous to the cracking chamber may be used for this purpose.

As a further alternative method of introducing the preheated oil vapors into the cracking system, the vapors from the preheater may be passed through lines 68 and 69 into cracking chamber 11b at a suitable distance below the surface of the metal stream. The vapors then are subjected to cracking at the high temperatures existing 65 within the cracking zone, and the resulting vapors combined with the cracked vapors produced from the preheated oil. Under the last mentioned mode of operation, therefore, the charging stock is subjected to both liquid and vapor phase cracking 70 within the same cracking zone. In view of the fact that the oil being introduced to the cracking zone through line 69 is already in vapor phase, it will ordinarily require less time in contact with the molten metal to effect the desired 75 conversion. Consequently, the vapors will usually

be introduced at a point 70 above the point of entry of the liquid oil stream to the cracking zone through line 26. It may be further mentioned that in addition to effecting both liquid and vapor phase cracking of the stock, the introduction of vapors through line 69 to the cracking chamber has the additional advantage of facilitating the removal of carbon residue from the surface of the metal stream by reason of the increased vapor velocity.

10 Lines 69 and 64 are connected by a pipe 71 containing a check valve 72, similar check valves 73, 74 and 75 being inserted in lines 63 and 68 at the points indicated. All these check valves seat counter-current to the flow of vapors through 15 the lines in the directions indicated by the arrows, and, together with the pressure balance line 66, are provided for the purpose of preventing the molten metal in the cracking chamber from being forced back through pipes 65 or 69 into the vapor 20 lines. If for any reason the pressure in vapor line 61 should drop to the extent that the vapor pressure in chamber 11a would tend to expel the molten metal through the vapor lines, the check valves will immediately seat and arrest surging of 25 the metal.

30 In order that reformation of the cracked vapors may be allowed to take place to the fullest possible extent within practical limitations, I preferably maintain the cracked vapors in an enlarged conversion chamber for a predetermined period of time, prior to preliminary condensation or fractionation. For this purpose, the vapors leaving carbon trap 20 through lines 77 and 78 may be discharged into an enlarged conversion 35 chamber 23 of such capacity that a time period of at least one or two minutes will be required for the vapors to flow through to the outlet 79. By thus holding the vapors in the chamber for a time interval, dissociation and reformation of 40 the cracked hydrocarbons are allowed to approach completion while the oil is held in vapor phase.

45 Back pressure valve 80 in the conversion chamber outlet line 79 may be set to maintain any suitable back pressure on the entire system. While ordinarily it will be preferred to crack the oil at a pressure not above atmospheric, valve 80 may be set to greatly increase the cracking pressure, say up to 100 lbs. per sq. in. or above. 50 It will be understood without the necessity for further illustrations in the drawings that after leaving the conversion chamber, the vapors may be further treated or fractionated by any of the usual methods and apparatus adaptable for the 55 purpose. It may be mentioned that in case the conversion chamber 23 is used, carbon trap 20 may be dispensed with and the carbon residue separated from the cracked vapors within the conversion chamber itself. In this case, the carbon trap will be bypassed by a line 81 connecting pipes 53 and 58 with the conversion chamber inlet line 78.

60 In starting the system into operation and before the heat transferring metal 25 is put into the system, the apparatus may first be brought up to operating temperatures by passing superheated steam through the molten metal circulating system. The steam may be introduced at any suitable point, as by way of line 82 connecting with the molten metal pump discharge line 34. After operating temperatures have been reached, the heat conducting metal 25 may be introduced at any suitable point, as by way of 70 pipe 83 in the top of cracking chamber 11a. 75

After all the metal has been introduced and circulation established, the system is started into operation by opening valve 36 and injecting the preheated charging stock into the cracking chamber. In shutting down the system, the oil and vapor lines leading to the cracking chamber are closed and the molten metal drained from the cracking chamber through outlet 38.

In a typical operating cycle, charging stock having a gravity in the neighborhood of 22.6° A. P. I. is preheated in still 37 to a temperature of around 640° F. The preheated oil is then introduced at this temperature to shell 17 wherein, during the time it flows upwardly in contact with the molten metal stream, the oil is heated to around 1130° F. at substantially atmospheric temperature. As a result of operations under substantially these conditions, I have been able to obtain a pressure distillate yield of approximately 99% calculated on the basis of the volume of charging stock. The gasoline yield recoverable from the pressure distillate, either by redistillation of the latter or by fractionation of the cracked vapors, has been found to run as high as 88% of the charging stock volume. As previously observed, tests made upon gasoline refined in accordance with the invention have indicated octane ratings running as high as 86%, and have shown the product to be substantially free of sulphur and residual corrosive or gummy substances.

I claim:

1. The method of cracking hydrocarbons that includes, pumping a stream of molten metal in a circuitous path of flow through a heating zone and then through a cracking zone, preheating and partially vaporizing an oil charging stock, separating the vapors from the unvaporized oil, discharging the preheated oil directly into the molten metal within the cracking zone, heating the oil during its contact with the molten metal to a temperature at which the oil is cracked and entirely vaporized, leaving a carbon powder residue on the surface of said metal stream, continuously removing said residue from the cracking

zone in a stream of cracked oil vapors, and conducting oil vapors produced in said preheating operation into said cracking zone.

2. The method of cracking hydrocarbons that includes, pumping a stream of molten metal in a circuitous path of flow through a heating zone and then through a cracking zone, preheating and partially vaporizing an oil charging stock, separating the vapors from the unvaporized oil, discharging the preheated oil directly into the molten metal within the cracking zone, heating the oil during its contact with the molten metal to a temperature at which the oil is cracked and entirely vaporized, leaving a carbon powder residue on the surface of said metal stream, continuously removing said residue from the cracking zone in a stream of cracked oil vapors, and combining with said cracked vapors, oil vapors produced in said preheating operation by introducing the last mentioned vapors into the molten metal within the cracking zone.

3. The method of cracking hydrocarbons that includes, maintaining a body of molten metal within a cracking zone, preheating and partially vaporizing an oil charging stock, separating the vapors from the unvaporized oil, introducing the preheated oil directly into the molten metal within said cracking zone, heating the oil during its contact with the molten metal to a temperature at which the oil is cracked and vaporized, leaving a residue on the surface of the metal stream, withdrawing cracked vapors and residue from the cracking zone, and introducing vapors from said oil preheating operation into the molten metal within said cracking zone.

4. The method that includes, maintaining a body of molten metal within a cracking zone, preheating and partially vaporizing an oil cracking stock, separating the vapors from the unvaporized oil, introducing at least a portion of the unvaporized preheated oil into said body of molten metal, and separately introducing at least a portion of the vapors from the preheated oil into said body of molten metal.

GEORGE C. PECKHAM. 45
